UNITED STATES PATENT OFFICE.

WILLIAM K. SMITH, OF LA HARPE, ILLINOIS.

CARPET-STRETCHER.

SPECIFICATION forming part of Letters Patent No. 299,691, dated June 3, 1884.

Application filed March 17, 1884. (No model)

To all whom it may concern:

Be it known that I, WILLIAM K. SMITH, a citizen of the United States, residing in La Harpe, county of Hancock, State of Illinois, have invented a new and useful Carpet-Stretcher, which consists of an india-rubber sole or sandal, to be used in pairs or singly, made with serrated ridges or teeth extending across the bottom of sole.

10 The stretchers are to be fastened to the bottom of the boot or shoe of individual stretching carpet.

15 The mode of using is a kicking sliding motion of the feet. The weight of the body holds the carpet to its place after it has been drawn tight. After first fastening one edge of carpet to the floor the stretching can be done with perfect ease by the operator and without any injury to the carpet whatever, the hands being used for tacking and fastening only. I attain these objects by the mechanism illustrated in the accompanying drawings, in which—

20 Figure 1 is a side view of my carpet-stretcher. Fig. 2 is a bottom view showing serrated ridges or teeth for holding carpet.

Similar letters of reference refer to similar parts throughout the several views.

25 N is a sole, to conform to bottom of shoe or boot. A are serrated ridges or teeth extending across the bottom of front of sole of carpet-stretcher inclining forward. E are ser-

rated ridges or teeth on heel inclining backward.

In carrying out my invention, I prefer to make my carpet-stretcher with serrated teeth 35 inclining forward on front part of sole for stretching forward, and the teeth on heel inclining backward for the purpose of drawing the carpet toward the operator and for correcting any distortions of figures in carpet occurring from any error in forward stretching. I also prefer to make the teeth to extend continuously or in sections across the sole N. I further prefer to make the carpet-stretcher in the form of a sole with fastenings, that they 45 may be worn on the bottom of an ordinary shoe or boot, as the heel of shoe will prevent or hold the stretcher from slipping backward.

Having thus fully described my invention, that which I claim as new, and do desire to 50 secure by Letters Patent, is—

1. An india-rubber sole carpet-stretcher, to be operated by the feet, as set forth.
2. The serrated inclined teeth A and E, either extending across the sole of stretcher 55 or in sections, substantially as and for the purpose herein set forth.

WILLIAM K. SMITH.
